Inventor

Wm H. Wheeler

UNITED STATES PATENT OFFICE.

WILLIAM HENRY WHEELER, OF MOHAWK VILLAGE, OHIO.

HALTER.

SPECIFICATION forming part of Letters Patent No. 363,033, dated May 17, 1887.

Application filed March 15, 1887. Serial No. 231,034. (No model.)

To all whom it may concern:

Be it known that I, WILLIAM HENRY WHEELER, a citizen of the United States, residing at Mohawk Village, in the county of 5 Coshcocton and State of Ohio, have invented new and useful Improvements in Halters, of which the following is a specification.

My invention relates to improvements in halters; and its object is to provide improved 10 means for fastening the crown-piece, the nose-band, and the chin strap together.

To this end the novelty consists in the peculiar features of construction, combination, and arrangement of the parts, as hereinafter fully 15 described, and pointed out in the claims.

In the drawings, Figure 1 is a perspective view of a halter having my improved device applied thereto. Fig. 2 is a perspective view 20 of a section of the halter. Fig. 3 is a sectional view taken centrally through the plates. Figs. 25 4 and 5 are detail perspective views of the locking-plates. Fig. 6 is a section similar to Fig. 3, but taken at right angles thereto. Fig. 7 is a perspective view of the plates locked together, but with the straps removed.

Referring to the drawings by letter, A designates the nose-band, B the crown-piece, and C the chin-strap, which are arranged in the usual manner relative to each other, as will be 30 readily understood from the drawings. As will be readily understood, the crown-piece passes up over the head of the animal, the nose-band across the face, and the chin-strap back of or below the chin. The hitching rope or 35 strap is attached to the chin-strap, as shown.

The ends of the nose-band and crown-piece are held together by and between the independent removable locking-plates D E, and the chin-strap is held by having its ends passed 40 through loops e, which are formed integral with the plates E, and project from the rear edge thereof. The outer face or side of the plate E is provided with a flange, F, which is formed along the upper and lower and rear edges of 45 said plate. The ends of this flange F are provided with recesses or notches f, which, as shown, are at the opposite ends of the front edge of the plate. The function of these notches will be hereinafter set forth.

It will be readily seen that the construction 50 of the plate, as just described, forms a depre-

sion in its outer face, and the end of the nose-band is placed in this depression and held therein, as will be presently described. At the center of the plate I form an opening, g, 55 and around the inner edge of said opening I provide the cylindrical tongue or projection G. This projection G is internally screw-threaded, and the screw-thread extend through the opening in the plate. The outer plate, D, 60 is provided with flanges H I at its front and rear edges, respectively, and also has a central perforation or opening, d, as shown. This opening d is countersunk, as shown, and the retaining-screw J is passed through this opening into the opening g in the plate E and made to engage the said opening g in the operation of the device. The flange H at the front edge of the plate D is provided at its opposite ends with the points, lugs, or projections h, 70 and when the device is applied to the halter these points h engage the notches f, the nose-band being held between them. The flange I is deeper than the flange H, and has its opposite corners cut away, as at i. 75

In use the end of the nose-band is placed in the depression in the plate E, and fitted over the tongue G by means of a perforation provided for that purpose. The end of the nose-band does not extend to the rear edge of the 80 plate E, but stops a short distance therefrom, leaving an open space between the end of the strap and the flange along the edge of the plate, as shown in Fig. 6. The end of the crown-piece is placed against the inner face of the 85 plate D, resting between the flanges H I. The crown-piece and plate D are placed upon the nose-band and the plate E, the flange I resting in the space between the end of the nose-band and the flange F, and the points h fitting in the 90 recesses or notches f. The retaining-screw is then passed through the plates, the crown-piece, and the nose-band to secure the several parts together.

It will be seen from the foregoing that the 95 several parts are securely fastened by means of a single screw, and that the construction of the plates and arrangement of the flanges prevent the parts rotating one upon another. The end of the crown-piece is provided with a series of perforations, b, and the halter can be 100 made to fit any sized head by adjusting one or

another of these perforations to be engaged by the retaining-screw, as will be readily understood.

The several parts are all removable, and in case one strap or plate becomes broken, or is rendered useless in any way, it can be easily replaced without necessitating the provision of an entirely new halter.

Having thus described my invention, what I claim, and desire to secure by Letters Patent, is—

1. The combination of the plate E, having a depression in its outer face to receive the end of the nose-band, the nose-band, the crown-piece arranged over the nose-band, and the plate D, secured over the crown-piece and engaging the plate E, to hold the several parts together, substantially as specified.

2. The combination of the plate E, having a depression closed on three sides, the nose-band having its end fitted in this depression, but not extending to the rear side thereof, the crown-piece placed over the nose-band, and the plate D, secured over the crown-piece, and

having the flange I, fitting between the end of the nose-band and the rear end of the plate E, substantially as set forth.

3. The combination, with the nose-band and crown-piece, of the locking-plates D E, provided with the interlocking flanges F and H I, respectively, which mutually engage and hold the several parts against rotation, substantially as set forth.

4. The combination, with the nose-band and the crown-piece, of the independent locking-plates having mutually-engaging flanges, the flanges of one plate having the notches f, and the flanges on the other plate having points which fit in said notches, substantially as described and shown.

In testimony that I claim the foregoing as my own I have hereto affixed my signature in presence of two witnesses.

WILLIAM HENRY WHEELER.
